(57) CLAIM

The ornamental design for a plant pot as shown and described.

DESCRIPTION

FIG. 1 is a bottom perspective view of a plant pot showing my new design;

FIG. 2 is a front elevational view thereof;

FIG. 3 is a back elevational view thereof;

FIG. 4 is an enlarged top plan view thereof; and,

FIG. 5 is an enlarged bottom plan view thereof.

The broken lines depict portions of the pot that forms no part of the claimed design.
